(57) **CLAIM**

The ornamental design for a high current power connector, as shown and described.

DESCRIPTION

FIG. 1 is a top, front and left perspective view of a high current power connector, showing our new design;
FIG. 2 is a bottom, rear and right perspective view thereof;
FIG. 3 is a top plan view thereof;
FIG. 4 is a bottom plan view thereof;
FIG. 5 is a front elevation view thereof;
FIG. 6 is a rear elevation view thereof;
FIG. 7 is left side elevation view thereof; and,
FIG. 8 is right side elevation view thereof.
